(57) **CLAIM**

The ornamental design for the fishing reel leg, as shown and described.

DESCRIPTION

FIG. 1 is a perspective view of the fishing reel leg according to the present invention with the fishing reel shown in phantom lines;

FIG. 2 is a side elevational view of FIG. 1 with a portion of the phantom lines shown;

FIG. 3 is a front elevational view of FIG. 1;

FIG. 4 is a top plan view of FIG. 1;

FIG. 5 is a rear elevational view of FIG. 1;

FIG. 6 is a bottom plan view of FIG. 1;

FIG. 7 is a perspective view of another embodiment of the fishing reel leg according to the present invention with the fishing reel shown in phantom lines;

FIG. 8 is a side elevational view of FIG. 1 with a portion of the phantom lines shown;

FIG. 9 is a front elevational view of FIG. 1;

FIG. 10 is a top plan view of FIG. 1;

FIG. 11 is a rear elevational view of FIG. 1;

FIG. 12 is a bottom plan view of FIG. 1;

FIG. 13 is a perspective view of a further embodiment of the fishing reel leg according to the present invention with the fishing reel shown in phantom lines;

FIG. 14 is a side elevational view of FIG. 1 with a portion of the phantom lines shown;

FIG. 15 is a front elevational view of FIG. 1;

FIG. 16 is a top plan view of FIG. 1;

FIG. 17 is a rear elevational view of FIG. 1;

FIG. 18 is a bottom plan view of FIG. 1;

FIG. 19 is a perspective view of a still further embodiment of the fishing reel leg according to the present invention with the fishing reel shown in phantom lines;

FIG. 20 is a side elevational view of FIG. 1 with a portion of the phantom lines shown;

FIG. 21 is a front elevational view of FIG. 1

FIG. 22 is a top plan view of FIG. 1;

FIG. 23 is a rear elevational view of FIG. 1; and,

FIG. 24 is a bottom plan view of FIG. 1.

The broken line showing of environment in the drawings is included for the purpose of illustrating only and forms no part of the claimed design.
